UNITED STATES PATENT OFFICE.

EDWIN R. THOMAS, HENRY POKORNEY, AND CARL THORDEN, OF BUFFALO, NEW YORK; SAID POKORNEY AND THORDEN ASSIGNORS TO SAID THOMAS.

DESIGN FOR A FRAME FOR MOTOR-VEHICLES.

SPECIFICATION forming part of Design No. 33,973, dated January 22, 1901.

Application filed December 24, 1900. Serial No. 40,977. Term of patent 7 years.

To all whom it may concern:

Be it known that we, EDWIN R. THOMAS and HENRY POKORNEY, citizens of the United States, and CARL THORDEN, a subject of the King of Sweden and Norway, residing at Buffalo, in the county of Erie and State of New York, have invented and produced a new and original Design for a Frame for Motor-Vehicles, of which the following is a specification, reference being had to the accompanying drawing, forming a part thereof.

This design relates to the configuration of a frame for motor-vehicles.

The accompanying drawing is a perspective view of a frame for motor-vehicles embodying our design.

The leading feature of our design consists of the peculiar shape of the longitudinal side bars, the longitudinal reach, and the steering-head of the motor-vehicle frame.

As shown in the drawing, the central reach consists of a straight central part *a*, a rear part *b*, which curves upwardly and rearwardly from the central part *a* to a rear transverse bar *D*, and a front part *e*, which curves upwardly and forwardly from the central part *a* to the lower end of the vertical steering-head *F*. Each of the side bars consists of a straight central part *G*, which is arranged parallel with the central part of the

reach, a straight rear part *H*, which is arranged higher than the central part *G* and farther away from the reach, a reversely-curved part *g*, connecting the rear end of the central part *G* with the front end of the rear part *H*, and a front part *g'*, which curves from the front end of the central part *G* upwardly, forwardly, and inwardly to the upper front part of the steering-head *F*. The front portions of the side bars and reach are connected by straight cross-bars *i i'*, arranged one behind the other, and the rear portions of the side bars and reach are connected by a cross-bar *i''*, which curves from the reach upwardly to the side bars. The central part of the rear transverse bar is provided with depending hangers *k*, and the outer ends of this bar are provided with depending hangers *k'*, which unite with the rear ends of the side bars.

What we claim is—

The design for a frame for motor-vehicles, substantially as herein shown and described.

Witness our hands this 11th day of December, 1900.

EDWIN R. THOMAS.
HENRY POKORNEY.
CARL THORDEN.
